UNITED STATES PATENT OFFICE

ALEXANDER H. GOURLAY, OF LOMBARD, AND CLIFFORD W. SKOGH, OF CHICAGO, ILLINOIS, ASSIGNORS TO MAGILL-WEINSHEIMER COMPANY, OF CHICAGO, ILLINOIS, A CORPORATION OF ILLINOIS

INDOOR PUTTING GREEN

Application filed April 19, 1929. Serial No. 356,365.

This invention relates to an indoor putting green and has for one object the provision of a device for the practice of putting indoors. The device may be used as a game if desired, but in any case is adaptable for indoor putting or indoor putting practice. Among the objects of the invention are the provision of such an indoor putting green or device which shall be simple to manufacture, easy to ship, and easy and practical to assemble. Other objects will appear from time to time in the course of the specification and claims.

The invention is illustrated more or less diagrammatically in the accompanying drawings, wherein—

Figure 1 is a plan view of the device unfolded;

Figure 2 is a plan view of the device assembled;

Figure 3 is a section on the line 3—3 of Figure 1;

Figure 4 is a side elevation;

Figure 5 is a vertical section along the line 5—5 of Figure 4;

Figure 6 is a section on the line 6—6 of Figure 4;

Figure 7 is a detail; and

Figure 8 is a partial section through a modified form.

Like parts are indicated by like symbols throughout the specification and drawings.

Referring for example to the device in its extended or unassembled condition, as shown in Figure 1, it includes a central panel A of cardboard, fiber or any other suitable material, which is provided with side panels A¹ A². The said three panels each is provided along its lower edge with adjacent panels A³, A⁴ and A⁵, these various panels being separated from each other by scoring, rouletting, perforating or the like, as at B, in such fashion that the panels can be bent in relation to each other, along such lines. The panels A¹ and A² are provided with the lateral foldable connecting portions C C¹ and the panels A⁴ A⁵ with lateral folding portions C² C³. Foldably secured to the top of the panel A is the portion C⁴ which has foldably secured to one side a lateral extension C⁵ and to the other side a lateral extension C⁶. Note that the

members C⁵ and C⁶ are provided with slots or apertures C⁷ properly formed to receive the securing members or tongues C⁸ C⁹ formed on the panels A¹ A² and on their lateral extensions C and C¹, as shown in Figure 1. 55

In assembling the blank to form the device as shown in Figure 2 the member C⁴ is folded along the line C⁹ to bring it into the position in which it is shown in Figure 5. Then the portions C⁵ and C⁶ are bent into 60 the position in which they are shown in Figure 2 and the tongues C⁸ are passed through the apertures C⁷, as is also shown in Figure 2. The result is a bracing or assembly of the device and a lifting of the upper edge of the 65 panels A, A¹, A², more or less above the floor level.

In order to support the forward edge of the device and to lift it somewhat above the floor level, we may provide any suitable means for 70 example the cleat generally indicated as D and shown in detail in Figure 7. The central portion D¹ may be gummed to the bottom of the panel A and the portions D² D³, which are in foldable relation therewith, may be 75 interlocked, as shown in section in Figure 6, with the tongue D⁴ passing through the cut away portion D⁵, its edge penetrating the slot portions D⁶. The result is a support of the forward edge of the center panels, as 80 shown in section in Figure 5, with the panels A³, A⁴, A⁵ inclined downwardly towards the floor. In order to simulate the condition of a putting green we provide the various ball receiving apertures indicated for example as 85 E, there being, if desired, an aperture for each of the nine holes. The apertures may be of unequal diameters, as shown for example in Figures 1 and 2, and each aperture may be provided with a symbol to indicate 90 a different hole. We may find it desirable to have holes of different diameters. We do not wish to be limited to any precise spacing of the holes but we herein indicate three holes in each of the main panels. 95

To provide a penalty we may employ the cut away portion E¹ in the central panel A, this cut away portion being associated with the central support or ground engaging member E² associated with the panel C⁴. 100

The rules of the game or putting instructions or any other desired material may be printed at any suitable point. We prefer to print the material on the portions C⁵ C⁶ 5 where the print will not be worn by the constant passage of the balls thereover.

We may, if desired, provide cloth bags or similar securing means, indicated as E⁵ in Figure 8. These are helpful if the device is 10 made of such size and spaced sufficiently above the floor to permit the balls to roll about beneath it. The provision of bags makes the removal of balls from the apertures easier. We may find it desirable to 15 dispense with the bags, and in such case we may have the height of the panels above the floor less than the diameter of a golf ball. In such case the golf balls which penetrate the pockets or holes will be unable to roll in 20 under the panels or the top of the device. Note, as for example from Figure 6, that the panels are sufficiently close to parallelism with the floor that they may be made with a certain pitch sufficient to return the balls 25 which do not penetrate any of the pockets, while at the same time not elevating the rear of the panels high enough to permit balls to roll freely thereunder.

In folding the device for shipment consider it as initially laid out as shown in Figure 1. Considering the panel A, with its lower extension A³ and its upper extension C⁴ as the center of the device, the side panel A², the lower panel A⁵ and the member C⁶ 30 may be folded over the center and then the corresponding portions A¹ A⁴ and C⁵ may be folded over them. The cleat D, when in the position in which it is shown in Figure 5, lies flat, and of course the cloth bags E⁵ 35 take up no important space. The result is a putting green or putting game which may be shipped flat, which take a minimum space in shipping, which is easily folded into shipping form and as easily unfolded therefrom, and which is peculiarly easily assembled. 40 There are no separable parts, and nothing to be lost or separated from the device. However, the device, unassembled, is solid and strong.

It will be realized that whereas we have 45 described and shown a practical and operative device, nevertheless many changes might be made in the size, shape, number and disposition of parts without departing from the spirit of our invention. We therefore wish 50 our description and drawings to be taken in a sense diagrammatic and illustrative, rather than as limiting us to our specific showing.

We claim:

1. In an indoor putting green, a central panel, and a support for one edge thereof, side panels foldably secured thereto and a higher support for the opposite edge of the center panel, and supporting means for the 55 adjacent edges of the side panels.

2. In an indoor putting green, a central panel, and a support for one edge thereof, side panels foldably secured thereto and a higher support for the opposite edge of the center panel, and supporting means for the adjacent edges of the side panels, including 70 a member foldably secured to the edge of the central panel and adapted for securing engagement with the adjacent edges of the side panels.

3. In an indoor putting green, a central panel, and a support for one edge thereof, side panels foldably secured thereto and a higher support for the opposite edge of the center panel, and supporting means for the adjacent edges of the side panels, including 75 a member foldably secured to the edge of the central panel and adapted for securing engagement with the adjacent edges of the side panels, the edges of the side panels being inclined in relation to the edge of the center panel.

4. In an indoor putting green, a central panel, and a support for one edge thereof, side panels foldably secured thereto and a higher support for the opposite edge of the center panel, and supporting means for the adjacent edges of the side panels, including 80 a member foldably secured to the edge of the central panel and adapted for detachable securing engagement with the adjacent edges of the side panels.

5. In an indoor putting green, a central panel, and a support for one edge thereof, side panels foldably secured thereto and a higher support for the opposite edge of the center panel, and supporting means for the adjacent edges of the side panels, and apron members 85 forwardly extending from the lower edges of the center and side panels.

6. In an indoor putting green, a central panel, and a support for one edge thereof, side panels foldably secured thereto and a higher support for the opposite edge of the center panel, and supporting means for the adjacent edges of the side panels, including 90 a member foldably secured to the edge of the central panel and adapted for securing engagement with the adjacent edges of the side panels, and adapted to serve at the same time 95 as a back stop for the putting green.

7. In an indoor putting green, a central panel, side panels in foldable relation thereto, the central and side panels being provided with a plurality of golf ball receiving 100 apertures and foldable supporting means for the central and side panels, adapted to maintain them, when assembled, inclined somewhat from the horizontal.

Signed at Chicago, county of Cook and 105 State of Illinois, this 12th day of April, 1929.

ALEXANDER H. GOURLAY.
